Hubert & Beck Attorney.

UNITED STATES PATENT OFFICE.

EDGAR D. NEWKIRK, OF SYRACUSE, NEW YORK.

CAN OPENER.

Application filed August 21, 1925. Serial No. 51,597.

This invention relates to certain improvements in can openers; and the nature and objects of the invention will be readily recognized and understood by those skilled in the art in the light of the following explanation and detailed description of the accompanying drawings illustrating what I at present consider to be the preferred embodiments or mechanical expressions of my invention from 5 among various other forms, arrangements, combination, and constructions of which the invention is capable within the spirit and scope of the invention.

The invention is particularly directed to 15 those types of portable and manually operable can openers with which the end or head of a can is severed and detached from the can body by clamping the end flange or seam between rollers and cutting around the can side 20 wall below the end flange with a rotary cutter; and one of the objects of the present invention resides in the provision of a mounting and arrangement of the rollers and the rotary cutter, on and with the operating levers or 25 handles of the can opener, such that the rollers and cutter are readily movable to and from operative position on and clamping a can end, and in which the rotary cutter with the can opener applied to and clamped on 30 a can, is in position to efficiently and positively cut the can side wall and cleanly sever the can end therefrom.

A further object of the invention is to provide a can opener of the general type referred to, in which an advancing and clamping roller is mounted on a main operating lever or handle and a rotary cutter and clamping roller is mounted on a crosshead slidably carried by such lever for movement in a 35 straight line to and from operative position with the advancing lever, and which crosshead is operated by a lever fulcrumed at points offset from the main lever or handle, so as to develop direct and positive clamping 40 action of the rollers and position of the rotary cutter for smooth, positive cutting, with a minimum application of force to the operating levers.

Another object of the invention is to provide a can opener of the rotary cutter-can end severing type, of simple construction for 45 relatively inexpensive production, while retaining the characteristics of ease of operation and durability in service, and positive 50 and efficient operation in the hands of the average user.

A further object of the invention resides in the design and construction of a can opener of the rotary cutter-can end severing type, which will form and provide an opener for 55 removing bottle caps of the crown or similar types without lowering the efficiency of or mechanically complicating the can opener.

With the foregoing general objects, and certain other objects and results in view, 60 which other objects and results will be readily apparent from the following description, the invention consists in certain novel features in construction and in combination and arrangement of elements, as will be more fully 65 and particularly referred to and specified hereinafter.

Referring to the accompanying drawings, in which similar reference characters refer to corresponding parts throughout the several figures thereof:

Fig. 1 is a top plan view of a can opener embodying the invention, in applied, clamped position on a can for severing the can end, a portion of the end of the can and end flange 80 thereof being shown.

Fig. 2, is a top plan view of the can opener in opened position for receiving and application to a can and the end flange or seam thereof.

Fig. 3, is a fragmentary view, partly in section, showing the construction and mounting of the sliding crosshead carrying the rotary cutter and clamping roller, on the main operating lever or handle with the advancing 85 roller.

Fig. 4, is a vertical section through the crosshead and main operating lever with the rollers and cutter in open, can receiving position.

Fig. 5, is a vertical section through the crosshead and main lever or handle, and through the clamping roller and rotary cutter, with the can opener in applied position 90 on a can, a portion of the can and end flange 100 being shown in a vertical section with the cutter in position for severing the can side wall.

Fig. 6, is a view in side elevation of the can opener applied to a bottle cap and in position 105 for operation to remove the cap from a bottle, a portion only of the bottle being shown.

According to the embodiment of the invention disclosed herewith, purely by way of example and not of limitation, to illustrate the principles and features of the invention, the can opener includes the elong-

gated, substantially flat main lever or handle 10 having a spindle or stub shaft 11 disposed transversely therethrough, adjacent one end thereof and rotatably journaled 5 therein. At one side of lever 10, the spindle or shaft 11 is formed with a head 12 extending therefrom and having a bearing flange 14 in engagement with the adjacent side face of lever 10, while at the opposite 10 side of main lever 10, spindle or shaft 11 is extended and the advancing and clamping roller 15 is fixed thereon for rotation therewith in position adjacent to and bearing on the side face of lever 10 (see Figs. 4 and 15 5). The roller 15 has the edge or peripheral face thereof knurled, toothed, or milled, in the present instance the outer portion of its width only, to form an engaging and gripping surface 16. The spindle or shaft head 20 12 is transversely slotted or grooved at its outer end and a handle 17 is fixed in said groove by pin 18 and extends transversely of and beyond the head, with its outer ends oppositely curved or bent to form a handle 25 readily engaged and grasped by the fingers for rotating spindle or shaft 11, and the advancing roller mounted thereon.

The main lever or handle 10 is formed with an elongated slot 19, disposed longitudinally thereof in line with the shaft or spindle 11, and spaced inwardly and terminating at its outer end a distance from the advancing roller 15, as will be clear by reference to Fig. 3 of the drawings in particular. 30 Opposite the slot 19, the lever 10 is provided with a laterally projecting fulcrum forming arm 20, disposed in the plane of lever 10 and extending from one edge thereof substantially perpendicularly with respect to the slot 19, with the longitudinal axis of arm 20 approximately alined with the transverse center axis of the slot 19.

A crosshead 21, in the example hereof, of deep channel or U-shape in cross section, having spaced, substantially parallel side walls or flanges joined at one side thereof by the edge wall 22, and open at the opposite side edge and at the opposite ends, is provided for mounting over and sliding movement on 40 the main lever or handle 10. The crosshead 21 is provided with an opening 23 through the edge wall 22 thereof, of a width slightly greater than the width of the fulcrum arm 20 projecting laterally from main lever 10, 50 and the crosshead is fitted over, and receives the lever 10 between the spaced side walls thereof, as shown particularly by Figs. 4 and 5 of the drawings, with the arm 20 extending through opening 23 and projecting 55 outwardly therebeyond. (See Figs. 1, 2, and 3.) The crosshead 21 is of greater width than the width of lever or handle 10, and the opening 23 is so positioned therein that with the crosshead mounted over arm 20 and lever 60 65 10, the forward portion of the crosshead ad-

acent the open edge thereof, is positioned over the slot 19 in the lever handle 10.

The forward outer portion of the crosshead 21 is formed with alined bores through the spaced side walls, which bores are alined 70 with and open into the lever slot 19, and a headed stud 24 is mounted in these bores extending through the crosshead and the slot 19. The stud 24 is mounted with the head thereof disposed on the same side of lever 10 as the advancing roller 15, and the stud extends outwardly a distance beyond lever 10 and roller 15 (see Figs. 4 and 5), and is formed with a bearing portion 25 providing a shoulder 25' (see Fig. 5) which abuts 80 against the adjacent flange or side wall of the crosshead 21. That portion 26 of the stud 24 disposed in and extending through lever slot 19 is of a diameter substantially equal to the width of slot 19 to form a sliding fit therein and the outer end portion 27 of the stud opposite bearing 25, is reduced and extends outwardly through the adjacent flange or side wall of crosshead 21. A shoulder 26' (see Figs. 4 and 5) is formed between 90 portions 26 and 27 of stud 24 and bears against the inner side of the adjacent crosshead side wall. The outer end or reduced portion 27 of stud 24 is screw-threaded and a nut 28 and washer 29 are mounted thereon 95 and thereover, and secure stud 24 in position on and movable with the crosshead.

A combined clamping and cutting roller 30 is mounted and rotatably journaled on the bearing 25 of stud 24 between the head of the stud and the crosshead 21, and this roller 30 is formed, in the present example, with a cutting blade 31 extending therearound and outwardly therefrom at the outer end thereof, and disposed in a plane a slight 105 distance below the plane of the advancing roller. A handle 32, in the example illustrated herewith, integral with the crosshead 21 and forming a reduced continuation thereof, of channel section, extends from the inner 110 end or side of crosshead 21, along and co-extensive with the main lever handle 10. The handle 32 is so disposed that in position moved inwardly toward lever 10, it fits over and receives the lever and is substantially 115 parallel therewith. However, the invention is not limited to the form of handle 32 illustrated herewith as integral with crosshead 21, as various other forms and constructions may be used suitably attached or secured to 120 the crosshead.

The crosshead 21, so constructed and mounted, is slideable on and over the main lever handle 10 toward and from the advancing roller 15, to carry the clamping and cutting roller 30 toward and from roller 15, by swinging the handle 32 toward and from main lever handle 10. When handle 32 is swung, the crosshead 21 is fulcrumed on the laterally projecting arm 20 of lever 10, and 130

the crosshead is moved longitudinally of lever 10, with stud 24 sliding longitudinally of slot 19, and guided and maintained in the required path by the slot, so that the stud 24 and the roller 30 carried thereon move in a substantially straight line longitudinally of the lever 10, toward and from the advancing roller 15. The opening 23 through the edge wall 22 of crosshead 21, with the arm 20 extending therethrough form fulcrum points for the crosshead 21, offset laterally from the lever 10 and path of movement for the stud 24. The opposite edges of the opening 23 form fulcrum or bearing points 33 and 34 which engage and bear against opposite side edges of fulcrum arm 20, the bearing 33 engaging arm 20 when handle 32 is swung to move crosshead 21 inwardly along slot 19, and the bearing 34 engaging arm 20 when the crosshead is moved outwardly along slot 19 and lever 10, by handle 32.

In operation of the can opener to sever the end or head of a can for removal thereof, the handle 32 of the opener is swung outwardly away from the main lever handle 10 to the position shown in Fig. 2 of the drawings. This movement of handle 32 slides or moves the crosshead 21 with stud and roller rearwardly or inwardly along the main lever 10, the crosshead fulcrumed at bearing point 33 on arm 20, to position with stud 24 at the inner end of slot 19, and the roller 30 with blade 31 in position spaced inwardly on lever 10 from roller 15, as clearly shown in Fig. 4. The can opener in this open position of rollers 15 and 30, referring now to Figs. 1 and 5 of the drawings, is placed over the end or head of a can C with the advancing roller 15 disposed on the head of the can and the end flange or seam S of the can disposed between rollers 15 and 30. The handle 32 is then swung inwardly toward the main lever 10 and the crosshead 21 is moved thereby outwardly along lever 10, with the stud 24 sliding forwardly along slot 19 and the crosshead fulcrumed on bearing 34 engaged with fulcrum arm 20. The forward movement of crosshead 21 and stud 24 moves the roller and cutter 30 in a straight line outwardly and longitudinally of lever 10 toward the can C and advancing roller 15, and the movement of handle 32 and crosshead 21 is continued until the cutting blade 31 engages and penetrates the can side wall just below the end flange S, and the clamping roller 30 bears against the end flange and clamps the same between roller 15 and the roller 30. In this applied, operative position of the rollers, the cutting blade 31 extends inwardly through the can side wall and a distance inwardly below the advancing roller 15, as will be clear by reference to Fig. 5 of the drawings. Then by grasping the handle 32 and lever 10 in one hand with the application of pressure to maintain the end flange tightly clamped

between the rollers, and rotating the advancing roller 15 by handle 17 with the other hand, the can C is rotated between rollers 15 and 30 and the blade 31 cuts through and around the side wall of the can to completely sever the can end from the can body.

In carrying out that feature of the invention which provides for the use of the can opener above described to remove the caps or tops from bottles and the like, the main lever handle 10 is formed with the transversely inclined or beveled outer operating end to provide the jaw or bottle cap top engaging member 40, and the outer end of the crosshead 21 is formed with the projecting lip 41 as a continuation of the crosshead edge wall 22, to provide the bottle cap skirt or flange engaging member. In view of the fact that the outer side edge 22 of the crosshead 21 is spaced outwardly from the adjacent edge of lever 10, the jaw member 40 and lip 41 are spaced apart with member 40 extended outwardly beyond the lip 41.

Referring now to Fig. 6 of the accompanying drawings, a portion of a bottle B is shown closed by a cap T of the crown type forced and maintained under pressure thereon. In the operation and use of the can opener to remove the bottle cap T, the jaw member 40 of lever 10 is placed on the top of bottle cap T a sufficient distance thereover and thereacross to bring the projecting lip 41 of crosshead 21 below and in engagement with the depending lower edge of the cap skirt or flange, with the handle 32 in raised position swung against lever 10, as clearly shown by Fig. 6. Then by raising or swinging the outer ends of handles 10 and 32 upwardly on the jaw 40 as a bearing or fulcrum point, the lip 41 engaging the cap flange will force the cap from seated position on the bottle. Thus, the can opener is formed without mechanically complicating the same to likewise provide a simple and efficient bottle opener for removing bottle caps.

With the invention as a can opener, by the mounting and arrangement of rotary cutting and clamping roller 30 on cross-head 21 for movement in a straight line longitudinally of the main lever 10 toward roller 15 and into clamping and cutting engagement with the can, and rotation of the can through advancing roller 15, with the clamping and cutting roller 30 freely rotatable with the can, a smooth clean cut is secured and positive positioning and operation of the various elements obtained with the minimum application of force to the operating levers. The construction and mounting of the various elements of the can opener is such that they are readily manufactured and assembled, and a strong durable device in the hands of the user results, which device provides in the one instrumentality both a can opener and a bottle cap remover.

It is also evident that various changes, modifications, variations, and substitutions might be resorted to without departing from the spirit and scope of my invention, and 5 hence I do not desire to limit myself to the exact and specific disclosures hereof.

Desiring to protect my invention in the broadest manner legally possible, what I claim and desire to secure by Letters Patent 10 of the United States, is:

1. In a can opener, one handle having a lateral horn, and a rotary advancing roller mounted in one end of said handle and having an operating handle; in combination 15 with another handle loosely confined to said first named handle and forming a cross head confined to said first named handle to straight-line reciprocation longitudinally thereof toward and from said advancing roller, and a clamping and cutting roller carried by said cross head, said other handle forming said cross head having a lateral portion disconnected from said horn and arranged to abut the same and constitute the 20 fulcrum on which said other handle rocks to advance said clamping and cutting roller toward said advancing roller.

2. In a can opener, a handle at one end provided with an advancing roller having a 25 handle for rotating the same, said handle formed with a straight longitudinal slot, said handle also having a rigid horn extending laterally therefrom; in combination with another and cooperating handle having a portion 30 that is approximately U-shaped in cross section slidably overlapping the side faces of the first mentioned handle and formed with a transverse opening through its closed edge portion loosely receiving said horn and providing a fulcrum edge to abut said horn, said portion carrying a stud extending through 35 said slot and confined therein to straight line reciprocation longitudinally thereof, and a clamping and cutting roller carried by said 40 stud.

3. A can opener comprising a handle at one end provided with a rotary advancing roller having an operating handle, said handle having a straight-line longitudinal slot 45 arranged radially with respect to the axis of said roller, said handle having a relatively fixed fulcrum abutment arranged laterally of the handle a distance from said slot; in combination with another complementary

5 handle slidably overlapping the first mentioned handle and loosely confined thereto and provided with a stud confined in said slot to straight line reciprocation longitudinally thereof, and a rotary clamping and cutting roller carried by said stud, said other complementary handle having a relatively fixed fulcrum portion arranged laterally some distance from said stud to move to and abut and rock on said fulcrum abutment when the two handles are pressed toward each other to provide the leverage for advancing the clamping and cutting roller in a straight line toward the advancing roller.

4. A can opener, comprising a pair of complementary handles loosely coupled together 70 and carrying cooperating rotary advancing and cutting rollers having hand operating rotating means, said handles also having relatively movable disconnected portions rigid with their respective handles providing co-operating abutments having relative lateral and separating movements and arranged to come together for handle fulcruming engagement when said handles are pressed toward each other to bring said rollers into cooperative action on the can, the end of one handle carrying one of said rollers, and the end of the other handle the other roller, the axis of the cutting roller being spaced laterally a distance from said abutments and having a 75 straight-line path of reciprocation radially of the axis of the advancing roller.

5. A can opener comprising rotary cutting and advancing rollers having parallel axes and a rotating handle, and a pair of elongated handles, one of said handles having one of said rollers mounted at an end thereof, said handle also formed with a rigid lateral horn and an elongated slot spaced laterally from said horn; the other handle formed with a portion slidably overlapping the slotted portion of the other handle and having a stud 90 slideable in and longitudinally of said slot and carrying the other of said rollers and also having a rigid transverse portion spaced a distance laterally from said stud and formed with a transverse opening loosely receiving said horn and providing abutments relatively movable with respect thereto and formed to abut and fulcrum thereon.

Signed at Syracuse, New York, this 11th day of August, 1925.

EDGAR D. NEWKIRK.
